UNITED STATES PATENT OFFICE

LEWIS C. PACKER, OF LONGMEADOW, MASSACHUSETTS, ASSIGNOR TO WESTINGHOUSE ELECTRIC & MANUFACTURING COMPANY, A CORPORATION OF PENNSYLVANIA

DESIGN FOR A COMBINED CASING AND DUST BAG RECEPTACLE FOR A VACUUM CLEANER

Application filed March 2, 1931. Serial No. 38,892. Term of patent 7 years.

To all whom it may concern:

Be it known that I, LEWIS C. PACKER, a citizen of the United States, residing at Longmeadow, in the county of Hampden and State of Massachusetts, have invented a new, original, and ornamental Design for a Combined Casing and Dust Bag Receptacle for a Vacuum Cleaner, of which the following is a specification, reference being had to the accompanying drawings constituting a part hereof.

Figure 1 is a plan view of a combined

casing and dust bag receptacle for a vacuum cleaner, showing my new design,

Fig. 2 is a side view of the same,

Fig. 3 is a front view of the same.

I claim:

The ornamental design for a combined casing and dust bag receptacle for a vacuum cleaner substantially as shown.

In testimony whereof, I have hereunto subscribed my name this 20th day of February, 1931.

LEWIS C. PACKER.
